L. T. HOUGHTON.

THREAD GUIDE SUPPORT FOR SPINNING OR TWISTING MACHINES.

APPLICATION FILED SEPT. 10, 1908. RENEWED JAN. 21, 1915.

1,134,336.

Patented Apr. 6, 1915.

UNITED STATES PATENT OFFICE.

LEWIS T. HOUGHTON, OF WORCESTER, MASSACHUSETTS.

THREAD-GUIDE SUPPORT FOR SPINNING OR TWISTING MACHINES.

1,134,336.

Specification of Letters Patent.

Patented Apr. 6, 1915.

Application filed September 10, 1908, Serial No. 452,460. Renewed January 21, 1915. Serial No. 3,642.

To all whom it may concern:

Be it known that I, LEWIS T. HOUGHTON, a citizen of the United States, residing at Worcester, in the county of Worcester and

5 State of Massachusetts, have invented a new and useful Thread-Guide Support for Spinning or Twisting Machines, of which the following is a specification.

The object of this invention is to improve 10 the details of the thread guide support for spinning or twisting machines, shown, described and claimed in Reissue Letters-Patent granted to me August 23, 1904, No. 12,362 and also the adjusting and clamping 15 means for the thread guide shown, described and claimed in patent granted to me July 25, 1905, No. 795,769, and in patent granted to Clarence A. Pierce, April 4, 1905, No. 786,380.

20 To this end the invention consists of the parts and combinations of parts hereinafter described and illustrated in the accompanying drawing, forming part of this application for patent, in which,

25 Figure 1 is a plan view of a thread guide support constructed to embody my invention. Fig. 2 is a side elevation thereof. Fig. 3 is a front elevation thereof on the line 3-3 of Fig. 1. Fig. 4 is a cross sectional elevation. Fig. 5 is a perspective view of the thread guide clamp. Figs. 6 and 7 are a plan and front illustration of a modification, and Fig. 8 is a perspective view of the clamp used in the modification shown in 35 Figs. 6 and 7.

In my Reissue Patent No. 12,362 is shown a form of thread guide support which has gone into extensive use which support is made out of sheet metal having a base or 40 supporting part depending from which are side flanges and a front flange and which support is hinged to the doffing rail by a plurality of fingers extending from its rear edge which intermesh with a plurality of 45 fingers carried by the rail to form a hinge joint.

One object of the invention is to improve and simplify this hinge joint and to this end I provide the support with a single 50 smooth ear at its rear end which is bent around a wire or pintle carried by the rail or by a strip secured thereto. This provides an improved smooth hinge joint.

In my Patent No. 795,769, a means is 55 shown whereby the thread guide is pivoted

at one point and clamped at another thus providing a pivoting sidewise adjustment and an in and out adjustment and at two point support for the thread guide.

In said patent to Pierce No. 786,380 a 60 clamp is shown which can be adjusted laterally parallel to the thread guide and in which the thread guide can be adjusted in and out.

A second object of the present invention 65 is to combine in one structure, the good points of both these patents. To this end I provide a clamp which can be adjusted laterally on the support and which is held from turning thereon, which clamp has a two 70 point engagement with the shank of the thread guide pressing the same to the underneath side of the support thereby combining in one clamping means the advantages of sidewise adjustment of the clamp in lines 75 parallel with the shank of the thread guide and of a two point engagement of the clamp with the thread guide.

Further advantages tending to simplify and improve the parts will be hereinafter 80 described.

Referring to the drawing and in detail A designates the back or doffing rail which may be made of wood, as shown in Fig. 1 or out of metal as shown in Fig. 2 and secured to the front face thereof, is a sheet metal strip B which has ears 10-10 projecting therefrom which carry and support a pin or shaft 11.

C designates the thread guide support, 90 which is pressed or struck out of sheet metal so as to have depending side flanges 12-12, a front flange 13 and a projecting rear ear 14. The thread guide support is secured in place by bending the single ear 95 14 at the rear edge thereof around the pin 11 to form a hinge joint. By this construction a hinge is provided with less joints which prevents the accumulation of lint and which affords a smooth surface for cleaning.

Formed in the top surface of the thread guide support is a hole 16 and a depressed section 17 which forms a projection on the underneath surface of the thread guide support which holds the clamp D parallel to 105 the front flange of the support C and in engagement with the front flange. A screw or bolt 18 having a non-circular or square section 19 is inserted in the hole 16 and is provided with a nut 20 to engage the thread 110

guide clamp D. This thread guide clamp D is struck out of sheet metal so as to have two upwardly extending sides 21 which may have triangular notches therein to engage 5 the shank portion of the thread guide T at two points which is preferably made triangular in cross section. The thread-guide clamp is made slightly arched in shape, as illustrated in Fig. 8. Other shapes may be 10 given to the thread guide and notches.

The thread guide support C has a slot 22 through its front flange 13 so that the thread guide T may be moved sidewise. The clamp D has a slot 23 through which the screw 18 15 extends so that the clamp may be moved sidewise so that by loosening the nut on the bolt 18 a considerable degree of sidewise adjustment is obtained in the guide T and its clamp D which slides between the projection 20 17 and the front flange 13 of the thread guide support. The projection 17 thus forms a means for preventing the clamp from twisting and keeps the clamp in engagement with the front flange. By this arrangement 25 not only is a considerable lateral or sidewise adjustment for the thread guide T provided, but the thread guide can also be adjusted in and out in the clamp. The two flanges 21—21 of the clamp form two bearing points for holding the thread guide T and by using this two point bearing engagement and holding the clamp from twisting a simple and rigid clamping means is provided.

35 In the modification shown in Figs. 6, 7 and 8, the front flange 13 is cut down so as to form a reduced flange 130 and the front flange 21 of the clamp D engages the front side of the flange 130, the clamp D in this 40 modification having upwardly turned ears 132 with spaces 131—131 between the same and the flange 21, in which spaces the flange 130 fits. The ears 132—132, in this construction, thus comprise a means for holding the 45 thread-guide clamp in engagement with said front flange and thus correspond in function with the depressed section 17 of the first described modification. In both constructions, the clamp can be adjusted along the 50 flange, but as it is kept in engagement therewith, it will be held from turning and will be guided in parallel positions in its lateral adjustments. This is important, as the thread-guides often receive a blow or push

which may tend to move them sidewise and 55 thus out of adjustment.

It will be seen that in both constructions the clamp and hence the thread guide can be adjusted laterally or parallel to the front flange a considerable distance, and the two 60 point engagement of the clamp with the thread guide preserved. By these improvements, the cost of the manufacture is reduced and the article is simplified.

The proportion of the parts herein shown 65 and described may be varied by a skilled mechanic without departing from the scope of the invention, as expressed in the claims.

Having thus described my invention what 70 I claim is:—

1. In a thread board mechanism, the combination of a thread-guide support having a front, outside, downwardly depending flange, a thread-guide, and means for obtaining lateral adjustments of the thread-guide, comprising a thread-guide clamp for holding the thread-guide in fixed position, means for keeping the thread-guide clamp in engagement with the front flange to constrain the same from turning but to permit lateral adjustments of the same in parallel 75 positions, and means for tightening the clamp to engage the thread-guide.

2. A thread-guide support comprising a metal plate with a depending flange at its forward edge, a clamp having a longitudinal slot therein and having spaced, parallel, transversely notched edges, said notches fitting the shank of a thread-guide and preventing rotation thereof, a lug on the under side of said plate spaced from the forward flange of said plate a distance substantially equal to the width of said clamp, and fastening means extending through a perforation in said plate and through the longitudinal slot in said clamp, this construction permitting longitudinal adjustment of said clamp and lateral adjustment of said guide to parallel positions only, and said fastening means being effective to hold said clamp and 90 guide in adjusted position.

95 In testimony whereof I have hereunto set my hand, in the presence of two subscribing witnesses.

LEWIS T. HOUGHTON.
